A technical drawing of a mechanical component, likely a handle or lever. The drawing shows a main horizontal bar with a slot. A vertical post is attached to the left end of the bar. A circular component, possibly a pulley or a wheel, is attached to the post. The drawing is annotated with several numbers: '64' at the top, '44' on the left side of the bar, '42' on the right side, '49' at the bottom left, and '41' at the bottom right. The drawing is labeled 'Fig. 6'.

UNITED STATES PATENT OFFICE

JAMES C. WOODSON, OF MANSFIELD, OHIO, ASSIGNOR TO WESTINGHOUSE ELECTRIC & MANUFACTURING COMPANY, A CORPORATION OF PENNSYLVANIA

SLOT CLOSURE

Application filed February 28, 1931. Serial No. 518,930.

My invention relates to horizontal-chamber heat-treating furnaces of the endless overhead-conveyor type and more particularly to means for sealing the top slots in such furnaces.

An object of my invention is to provide a relatively simple and efficient slot-closure means for the top slot of a furnace.

In practicing my invention, I provide, in cooperation with an endless conveyor chain having depending material-supporting rods secured thereto and moving in the top slot of a furnace, a plurality of pivotally-mounted plates extending laterally of the slot and moved aside in sequence by the material-supporting rods against a resilient means which returns the plates to their initial slot-closing positions.

In the single sheet of drawing, Figure 1 is a view, in vertical lateral section, through a horizontal-chamber conveyor-type furnace with which is associated the device embodying my invention;

Fig. 2 is a fragmentary top plan view of the device embodying my invention;

Fig. 3 is a view, similar to Fig. 2, of a modified form of device embodying my invention;

Fig. 4 is a fragmentary view, in vertical section, of a still further modification of a device embodying my invention;

Fig. 5 is a fragmentary top plan view of the device shown in Fig. 4, and

Fig. 6 is a view in side elevation of two pairs of cooperating plates of the kind shown in Figs. 1 and 2.

Referring to Fig. 1 of the drawing, I have there illustrated a furnace structure 11, built up on a concrete base 12 and including a floor 13, side walls 14 and 16 and roof-wall portions 17 and 18, which may be built up of a plurality of bricks or blocks of a suitable refractory high-temperature resisting material, usually employed for such purposes.

The walls enclose a furnace chamber 19 and the roof-wall portions 17 and 18 are so located as to leave open a slot 21 therebetween which extends longitudinally of the horizontal-chamber furnace structure.

A skeleton metal frame includes vertical

structural steel members 22 and 23 and upper cross-bar members 24, it being understood that these members are spaced apart suitable distances along the furnace structure in order to provide a furnace-structure bracing framework, as well as a support for other elements to be hereinafter described.

Heating means for the furnace chamber 19 may include electric heating elements 26 and 27, suitably supported by the side walls 14 and 16.

I desire, however, that it be understood that, while I have illustrated and described a specific embodiment of such furnace elements, my invention is not restricted thereto and that these elements, illustrated generally only, are shown for illustrative purposes, and that the device embodying my invention is applicable to other furnace structures which may be effective for the same general purpose.

Means for moving material through the furnace chamber 19 includes an endless conveyor chain 28 which is movably suspended from the support by carriages 29 running on track sections 31 and 32 in the shape of angle bars, supported by auxiliary portions of the skeleton frame structure of which a specific embodiment is shown in the shape of vertical members 33 and 34 and short cross braces 36 and 37.

Material-supporting means include a plurality of spaced rods 38 secured to the chain 28, depending therefrom and moving in the slot 21. Cross bars 39 are secured to the respective rods 38 and have hooks 41 to directly support material to be heat-treated.

As it is apparent that the ends of the furnace chamber 19 must be open in order to permit the continuously moving conveyor to move material into, through and out of the furnace chamber, a large amount of hot air may flow upwardly through the slot 21, thereby reducing the efficiency of the furnace installations.

In order to prevent this, I provide two sets of opposing plates 42 and 43 which are pivotally mounted above the roof-wall portions 17 and 18 and intermediate their ends, as by suitable bolts 44 and 46, one for each plate.

The bolts 44 and 46 may extend through the plates 42 and 43, respectively, and into longitudinally extending metal members 47 and 48 defining a part of the upper side walls enclosing the slot 21, as shown more particularly in Fig. 1 of the drawing.

The inner ends of the plates 42 and 43 are located in abutting or slightly overlapping relation (see Fig. 6), and the plates themselves may be located either in abutting relation or, preferably, in overlapping relation at each side. Means for yieldingly holding the plates on each side in their normal positions, for permitting a turning movement on their respective pivots and for returning them to their normal positions is constituted by an open helical spring 49 associated with the plates 42 and a similar helical spring 51 associated with the plates 43. Each of the plates is provided with, say, an opening 52 at its edge and a link 53 connects the plates with the cooperating helical springs in substantially the manner shown in Fig. 2 of the drawing.

Fig. 2 of the drawing illustrates the movement of the respective plates 42 and 43 coincident with the movement of a depending material-supporting rod 38 therebetween, it being noted that one pair of plates 42 and 43 has been turned through a relatively large angle and that portions of the respective springs 49 and 51 have been deformed so that a succeeding pair of plates 42 and 43 which has just been disengaged from the rod 38 will not be permitted to return instantaneously to the normal position, as shown at the left-hand end of Fig. 2 of the drawing.

Referring more particularly to Fig. 3 of the drawing, I have there illustrated cooperating plates 56 and 57 located in side-by-side abutting or overlapping relation, each plate being pivotally mounted for turning movement in its own plane on a bolt 58. Helical springs 59 and 61 are located adjacent to the outer end portions of the plates 56 and 57, links 62 connecting the respective springs to the individual plates 56 and 57, in substantially the same manner as hereinafter set forth in connection with the elements shown in Fig. 2 of the drawing. It is obvious that the plates 56 and 57, the lengths of which extend angularly over the slot, instead of directly at right angles laterally thereto, will not be moved through such large angles on the respective pivots 58.

Referring now to Figs. 4 and 5 of the drawing, I have there illustrated roof-wall portions 63 and 64 in lateral section, the roof-wall portion 63 extending slightly higher than does the portion 64 and having an overhanging lip 66 to provide a shoulder portion having an angle-bar member 67 adjacent to its upper surface.

A rail 68 is suitably secured at the top of roof-wall portion 64, and relatively narrow

plates 69 are pivotally mounted in side-by-side relation on the rail 68, as by means of bolts 71. The respective plates 69 extend angularly across the slot 21 and have their inner ends spring-pressed against the angle bar 67 by helical springs 72, the individual spaced portions of which are connected, by links 73, to the outer ends of the plates 69. Normally, the plates 69 will be located in side-by-side or in parallel-extending overlapping relation, as shown in a portion of Fig. 5, and when a material-supporting rod 38 moves along the lip 66, which may be faced by a metal plate 74, the respective plates 69 will be moved forwardly and given a turning movement, the spring 72 permitting this and effecting return of the plates to their normal parallel-extending positions in which the inner ends extend over the lip 66 to substantially close the slot and thereby prevent outflow of heated air therethrough.

The device embodying my invention thus provides a relatively simple and efficient seal-closure means for the horizontal-chamber heat-treating furnace having a slot in its roof wall.

Various modifications may be made in my invention without departing from the spirit and scope thereof, and I desire, therefore, that only such limitations shall be placed thereon as are imposed by the prior art or are set forth in the appended claims.

I claim as my invention:

1. In a horizontal-chamber heat-treating furnace having a longitudinal slot in its roof-wall, an endless conveyor chain moving above said slot, and spaced material-supporting rods depending from the chain and moving in the slot, a slot-closure means including pivotally-mounted overlapping plates above the slot to be moved aside by a depending rod, and resilient means for yieldingly holding the plates in normal operative positions and for returning them thereto after movement thereof by a depending rod.

2. In a horizontal-chamber heat-treating furnace having a longitudinal slot in its roof-wall, an endless conveyor chain moving above said slot, and spaced material-supporting rods depending from the chain and moving in the slot, a slot-closure means including relatively narrow pivotally-mounted plates extending laterally over the slot and having their sides overlapping each other to be moved aside by the depending rods in passing through the slot, and resilient means on the plates for yieldingly holding them in normal operative positions and for returning them thereto after movement thereof by a depending rod.

3. In a horizontal-chamber heat-treating furnace having a longitudinal slot in its roof-wall, an endless conveyor chain moving above said slot, and spaced material-supporting rods depending from the chain and moving

in the slot, a slot-closure means including relatively narrow plates overlapping at their sides and extending laterally over the slot, means for pivotally mounting each plate intermediate its ends at one side of the slot on the roof-wall, and resilient means on the plates for yieldingly holding them in their normal operative positions and for returning them thereto after movement thereof by a depending rod.

4. In a horizontal-chamber heat-treating furnace having a longitudinal slot in its roof-wall, an endless conveyor chain moving above said slot, and spaced material-supporting rods depending from the chain and moving in the slot, a slot-closure means including relatively narrow plates overlapping at their sides and extending laterally over the slot, means for pivotally mounting each plate intermediate its ends at one side of the slot and on the roof-wall, whereby a depending rod engages the plates adjacent to one end thereof in succession to turn them aside, and resilient means engaging the other end of each plate to yieldingly hold them in normal operative positions and to return them thereto after movement thereof by a depending rod.

5. In a horizontal-chamber heat-treating furnace having a longitudinal slot in its roof-wall, an endless conveyor chain moving above said slot, and spaced material-supporting rods depending from the chain and moving in the slot, a slot-closure means including overlapping narrow plates extending substantially laterally over the slot and engaged adjacent to one end thereof by a depending moving rod, means for pivotally mounting each plate intermediate its ends on the roof-wall, and a helical spring loosely secured to the other end of each plate to yieldingly hold it in normal operative position and to return it thereto after pivotal movement thereof by a moving depending rod.

6. In a horizontal-chamber heat-treating furnace having a longitudinal slot in its roof-wall, an endless conveyor chain moving above said slot, and spaced material-supporting rods depending from the chain and moving in the slot, a slot-closure means including two sets of relatively narrow plates extending laterally over the slot in opposite directions with their adjacent inner ends in substantially abutting relation, means for pivotally mounting each plate intermediate its ends on the roof-wall, the pivotal mountings for each set being on opposite sides of the slot, and a helical spring secured to the plates of each set at the outer ends thereof.

In testimony whereof, I have hereunto subscribed my name this 14 day of February, 1931.

JAMES C. WOODSON.
